(57) **CLAIM**

The ornamental design for a register booster, as shown and described.

DESCRIPTION

FIG. 1 is a top perspective view of a register booster showing my new design;

FIG. 2 is a top plan view of the design shown in FIG. 1;

FIG. 3 is a front elevation view of the design shown in FIG. 1, the rear elevational view being identical;

FIG. 4 is a side elevational view of the design shown in FIG. 1; and,

FIG. 5 is another side elevational view of the design shown in FIG. 1.

The broken lines of FIGS. 1-5 illustrate portions of the register booster that form no part of the claimed design.
